UNITED STATES PATENT OFFICE.

JOHN HALTERBECK, OF NEW YORK, N. Y., ASSIGNOR TO GOTTFRIED PIEL, OF NEW YORK, N. Y.

WOODWORKING-VISE.

1,130,082.

Specification of Letters Patent.

Patented Mar. 2, 1915.

Application filed February 13, 1909. Serial No. 477,540.

To all whom it may concern:

Be it known that I, JOHN HALTERBECK, a subject of the Emperor of Germany, residing in the borough of Brooklyn of the city of New York, in the State of New York, have invented certain new and useful Improvements in Woodworking-Vises, of which the following is a specification, reference being had to the accompanying drawings, 10 forming a part hereof.

This invention relates to improvements in vises for holding wood or other material and has for its object to provide a mechanism which can be easily and readily adjusted in a variety of positions to receive articles of different sizes and of irregular shapes.

The invention consists in the new and novel features of construction and combinations 20 of parts hereinafter set forth and claimed.

In the accompanying drawings Figure 1 is a front elevation of a wood working vise embodying my invention, with the operating handle broken away. Fig. 2 represents a 25 section on the lines 2—2 of Fig. 1. Fig. 3 represents a plan view of the vise. Fig. 4 represents a sectional view on the lines 4—4 of Fig. 1. Fig. 5 represents a side view. Fig. 6 represents a section on the lines 6—6 30 of Fig. 2. Fig. 7 is a section on the lines 7—7 of Fig. 3.

The jaws 1 and 2 of the vise are secured to a plate 3 which may be attached in any suitable manner to a bench or table 4. Preferably a supporting frame 5 is pivoted as at 35 6 to a flange 7 on the plate 3, so that the vise as a whole may be tilted at an angle as shown in Fig. 5. An arm 8 is pivoted to the frame 5 and extends through a socket 9, 40 preferably formed integral with the plate 3. Said arm is secured in the socket, and the vise held in its adjusted position by a screw 10.

The rear jaw 1 is provided with a flange 45 11, rotatably mounted in a socket 12 formed in the frame 5 and secured against displacement by the split washer 13. A hand screw 14 holds the rear jaw against rotation in its adjusted position. Said jaw is also provided 50 with a hollow arm 16 forming a bearing for the sliding bar 24 and extends rearwardly a suitable distance and has secured thereto a plate 17 provided with a central bearing

18 having a portion of its circumference formed with an interrupted thread 19.

55

The front jaw 2 is provided with a rectangular central opening and with a flange 20 that seats upon a sleeve or casing 21 and is secured thereto so as to have a to-and-fro or rocking movement, by pins or screws 22. Said sleeve or casing is in turn mounted upon the squared end 23 of a hollow sliding bar 24, and both the jaw and the casing are permitted a limited tilting or sidewise movement thereon in a plane transverse to the plane of the rocking or to-and-fro movement, but are held against longitudinal movement by pins or screws 26. A screw 27 provided with an operating lever 28 is mounted in a bearing 29 formed in the sliding bar and in the plate 17, and is provided with an interrupted thread, as at 30, so that the sliding bar and the jaw can, if desired, be moved back and forth directly by the lever 28 without rotating the screw. The head 75 of the sliding bar has its sides cut away at 32, as shown in Fig. 4, to permit the sidewise movement of the jaw on the pins 26. After being adjusted the jaw is held in position by any suitable means as a clamping 80 screw 33 with a toothed flange or collar 34 adapted to engage co-acting teeth on the sleeve. A similar clamping screw 35 holds the jaw in position after it has been adjusted on the pins 22. Said clamping screws 33 85 and 35 pass through curved slots formed in the casing 21, which permit the desired adjustment of pins 22 and 26 to be made.

By means of this construction a vise is provided which can be readily arranged at 90 any desired angle with regard to the bench or table to which it is secured. Both of the jaws are movable with relation to each other, the rear jaw having a rotary movement independently of the front jaw, and 95 the front jaw having both a rocking or to-and-fro movement in a vertical or substantially vertical plane and a tilting or sidewise movement in a horizontal or substantially horizontal plane independently of the rear 100 jaw. Suitable means are also provided whereby the vise as a whole and each of the jaws independently may be securely held in any desired position. The vise is extremely compact in construction and may be 105 easily and readily assembled.

It is obvious that various changes in the details of construction may be made without departing from the spirit of the invention provided the means set forth in the following claims be employed.

I claim as my invention:

1. In a wood working vise, the combination of a frame, a rear jaw mounted on said frame and provided with a central bearing, a sliding bar movable in said bearing, a sleeve pivoted to said sliding bar and a jaw pivoted to said sleeve whereby said jaw may be rocked or tilted on said sleeve and may be rocked or tilted on said sliding bar in a plane transverse to the plane of said rocking or tilting movement on the sleeve.
2. In a wood working vise, comprising a relatively stationary jaw, a sliding bar, and a relatively movable jaw carried by said sliding bar, the combination with said sliding bar of a member pivoted to said bar, said member being secured to the movable jaw by a pivot arranged perpendicularly to said first mentioned pivot whereby both said member and jaw may be moved with relation to the sliding bar and said jaw may be moved independently of said member in a plane transverse to the plane of the first mentioned movement.
3. In a wood working vise the combination of a frame, a rear jaw mounted on said frame, a sliding bar movable on said jaw, a sleeve movably secured to the sliding bar by a pivot and having limited movement on said pivot, a jaw pivoted to said sleeve by a pivot arranged perpendicularly to said first mentioned pivot means for holding said jaw in its adjusted relation to the sleeve and separate means for holding said jaw and sleeve in their adjusted relation to the sliding bar.
4. In a wood working vise, the combination of a frame, a rear jaw rotatable on the frame and provided with a central bearing, a sliding bar movable in said bearing, a screw mounted in said sliding bar, a sleeve pivoted to said sliding bar, a front jaw pivoted to said sleeve, and means for holding said front and rear jaws in their adjusted positions respectively.
5. In a wood working vise, the combination with a pivoted frame, a rear jaw rotatably mounted on the frame and provided with a central bearing, a plate secured to said rear jaw and provided with an internally threaded bushing, and means for se-

curing said jaw in its adjusted position with relation to the frame, of a sliding bar movable in the bearing in said rear jaw, a screw provided with an interrupted thread rotatable in said sliding bar and adapted to engage the threads on said bushing to move said bar and a front jaw having an opening containing the end of the sliding bar, transversely disposed pins pivoting said jaw to said bar so that said jaw may be rocked or tilted with relation to the rear jaw in substantially perpendicular planes.

6. In a wood working vise, the combination with a front jaw, of a sliding bar movably mounted in said jaw, a screw rotatably mounted in said sliding bar for moving the same, a sleeve pivoted to said sliding bar and a front jaw pivoted to said sleeve, said sliding bar having a head provided on its top and bottom with a bearing for said sleeve and having its sides recessed to permit sidewise movement of said sleeve on its pivot, substantially as described.

7. In a wood working vise, the combination with a rear jaw, of a sliding bar, a sleeve mounted on said sliding bar, and means for holding said sleeve in its adjusted position comprising a set screw and a washer provided with teeth adapted to engage corresponding teeth on the sleeve, of a front jaw pivotally secured to said sleeve and provided with a flange having a slot formed therein, a set screw passing through said slot, and a washer on said set screw adapted to engage the surface of the jaw and hold same in its adjusted position.

8. In a wood working vise, the combination with a rear jaw, of a sliding bar movable axially with relation to said jaw, a screw for actuating said sliding bar, a sleeve mounted on said sliding bar, means for holding said sleeve against longitudinal movement with relation to said bar, but permitting a rocking movement thereon, a set screw between said sliding bar and sleeve, and a collar on said set screw engaging with the sleeve to hold the same in its adjusted position, and a front jaw secured to said sleeve.

This specification signed and witnessed this 30th day of January, A. D., 1909.

JOHN HALTERBECK.
